CLOTHES RACK

Harry J. Criner, Davenport, Iowa, assignor or
one-half to A. G. Bush, Davenport, Iowa

Application October 3, 1946, Serial No. 700,966

9 Claims. (Cl. 211—100)

1

My invention relates to improvements in clothes racks.

The objects of my invention are to provide a simple, inexpensive clothes rack which can be folded up so as to occupy a minimum of space; can be easily and quickly opened and adjusted and can be supported by a chair or similar support, with an alternate form that can be hung upon a hook or peg either on a side wall or on any form of pedestal support such as a chair or otherwise.

I attain these objects by the means illustrated in the accompanying drawings, in which,

Figure 1 is a front elevation of my rack as attached to the back of a chair;

Figure 2 is a top or plan view of the same as attached to the back of a chair;

Figure 3 is a side elevation showing the rack attached to a chair;

Figure 4 is an enlarged detail showing the method of supporting the arms;

Figure 5 is an enlarged sectional detail on the line 5—5 of Figure 4;

Figure 6 is an enlarged sectional detail on the line 5—5 of Figure 4, but showing the arms 3 in depending position;

Figure 7 shows a plan view of an alternate form;

Figure 8 a front view of such alternate form, and Figure 9 a side elevation of the alternate form;

Fig. 10 shows an alternate form of bracket for attaching the frame to the back of a chair.

Similar numerals refer to similar parts throughout the several views.

My apparatus comprises a frame 1 preferably composed of a flat bar of metal formed into elliptical form and having rigidly secured thereto a pair of brackets 2—2 having resilient legs spaced apart adapted to embrace the back bar 10 of a chair 11 or other suitable support.

These brackets 2 are preferably formed of resilient metal which will grip the back of a chair firmly, but as shown in Figure 10 at numeral 21, one leg of the bracket may be provided with a thumbscrew 8 threaded therein having a flat head formed upon the inner end and adapted to clamp the bracket firmly upon the bar 10.

A plurality of arms 3 are adjustably mounted upon the frame 1. The inner end of each arm 3 is provided with a slot 4 which is large enough to fit closely upon the flat bar frame 1. In order to secure the slotted ends of the arm 3 against splitting and in order to form a suitable hanger for them, I mount in the inner end of each arm 3 a heavy wire member 5 which passes through a suit-

2

able bore 41 formed in the end of each arm 3 adjacent the slot 4. The wire 5 is then bent down firmly against the edges of the arm 3 and holds firmly just as a rivet or bolt would do.

The outer portion of the wire 5 is formed into a ring shape adapted to surround the frame 1 and allow the arm to hang downwardly from the frame when the slot 4 is detached from the frame 1.

In constructing this device, I prefer to pass the wire 5 through the bore 41 in the end of the arm 3, then bend the wire down tightly against the arm and bend the free ends of the wire into the form of a ring 5 enclosing the frame 1. The ends 15 of the wire 5 are then soldered or spot-welded or otherwise secured together.

In the form of my apparatus shown in Figures 7, 8 and 9, the frame is bent on its long axis at right angles so that the upturned portion 6 may be placed in contact with a wall 12 and secured thereon by nails or screws 61 or other suitable means, the remaining half of the frame 1 being embraced within the slots 4 of the arms 3.

The arms may be of any desired length and 25 either round or square in section, but I have found a length of twenty-four to thirty inches satisfactory for most purposes.

While my apparatus is designed primarily to hang up small washings for drying purposes and 30 for hanging up freshly ironed articles to complete drying thereof, it may also be used to suspend heavy articles of clothing if desired.

When the apparatus is mounted upon a chair, the arms 3 may be spaced to extend in all directions so that the weight on the front arms 3 will 35 tend to counterbalance the weight upon the rear members to aid in preventing the chair from tipping over backwardly.

It is obvious that various modifications may be 40 made in the size, shape, arrangement and materials of the various elements without departing from the spirit of my invention and I do not limit my claims to the precise forms shown in the drawings.

45 I claim:

1. A clothes rack comprising a flat metal frame with supporting brackets rigidly united thereto whereby the brackets may straddle the back of a chair or other suitable support and secure the 50 frame thereto in horizontal position, a plurality of arms having their inner ends slotted to engage the frame and adapted to be held in horizontal position thereby, and means mounted upon the inner ends of the arms to reinforce the slotted portions against splitting and suspend the

arms from the frame when the slots are detached from the frame.

2. A clothes rack comprising an oval flat-metal frame with supporting brackets rigidly united thereto whereby the brackets may straddle the back of a chair or other suitable support and secure the frame thereto in horizontal position, a plurality of arms having their inner ends slotted to engage the frame and adapted to be held in horizontal position thereby, means mounted upon the inner ends of the arms to reenforce the slotted portions against splitting and suspend the arms from the frame when the slots are detached from the frame, said means comprising reenforcing wires respectively passing through the arms adjacent the inner ends of the slots and bent into rigid contact with the top and bottom of the arms adjacent the slots to prevent splitting of the arms and with the outer ends of the wires extended to encircle the frame and to suspend the arms from the frame when the slots are disengaged therefrom.

3. A clothes rack comprising an open flat-metal frame with supporting brackets rigidly united thereto whereby the frame may be secured in horizontal position upon the back of a chair or other suitable support, a plurality of arms having their inner ends slotted to engage the frame and adapted to be held in horizontal position thereby, and reenforcing wires respectively passing through bores in the arms adjacent the inner ends of the slots and bent into rigid contact with the sides of the arms on opposite sides of the slots to prevent splitting of the arms.

4. A clothes rack comprising an open flat-metal frame with supporting brackets rigidly united thereto whereby the frame may be secured horizontally upon the back of a chair or other suitable support, a plurality of arms having their inner ends slotted to engage the frame and adapted to be held in horizontal position thereby, and reenforcing wires respectively passing through bores in the arms adjacent the inner ends of the slots and bent into rigid contact with the top and bottom of the arms adjacent the slots to prevent splitting of the arms and with the outer ends of the wires extended to encircle the frame and to suspend the arms from the frame when the slots are disengaged therefrom.

5. In a clothes rack having a plurality of slotted arms, a reenforcing member for each arm comprising a heavy wire inserted in a bore in the arm adjacent the inner end of the slot and bent into rigid contact with the arm on opposite sides of the slot, the ends of the wire being then formed into a circular loop and rigidly united.

6. In a clothes rack for drying clothes, a semi-elliptical flat metal horizontal bar having a vertical support united thereto and a plurality of arms having their inner ends slotted to engage

the bar and to be held in horizontal position thereby, and wires mounted upon the inner ends of the arms arranged to reenforce the slotted portions against splitting and to suspend the arms from the bar when the slots are disengaged from the bar.

5 7. In a clothes rack having a plurality of slotted arms, a reenforcing member for each arm comprising a heavy wire inserted in a bore in the arm adjacent the inner end of the slot and bent into rigid contact with the arm adjacent the slot.

10 8. In a clothes rack, the combination with an open flat-metal frame, of brackets rigidly united thereto whereby the frame may be secured upon the back of a chair or other suitable support, a plurality of arms having their inner ends slotted to engage the frame and adapted to be held in horizontal position thereby, and means mounted upon the inner ends of the arms to reenforce the slotted portions against splitting and suspend the arms from the frame when the slots are detached from the frame, said means including reenforcing wires respectively passing through bores in the arms adjacent the inner ends of the slots and bent into rigid contact with the sides of the arms on opposite sides of the slots.

15 9. In a clothes rack, the combination with an open flat-metal frame, of brackets rigidly united thereto whereby the frame may be secured upon the back of a chair or other suitable support, a plurality of arms having their inner ends slotted to engage the frame and adapted to be held in horizontal position thereby, and means mounted upon the inner ends of the arms to reenforce the slotted portions against splitting and suspend the arms from the frame when the slots are detached from the frame, said means including reenforcing wires respectively passing through bores in the arms adjacent the inner ends of the slots and bent into rigid contact with the sides of the arms on opposite sides of the slots and with the outer ends of the wires extended to encircle the frame and to suspend the arms from the frame when the slots are disengaged therefrom.
